UNITED STATES PATENT OFFICE

DELOS P. HEATH, OF DETROIT, MICHIGAN

COMPRESSOR

Application filed January 6, 1928. Serial No. 78,559.

This invention relates to a compressor of the type which may be used for compressing gases. The compressor is not limited in use to the compression of any particular gas, though in practice I have designed it for use as the compressor in mechanical refrigerating apparatus.

It is a primary object and purpose of the present invention to make a compressor with which gases may be compressed wherein, on the stroke of the piston in one direction the gas to be compressed will be drawn through the piston into the cylinder and on the stroke of the piston in the opposite direction the gases will be compressed and forced outwardly to any suitable reservoir or other container for the compressed gas. Another object of the invention is to construct a compressor which, on the compression stroke of its piston, will completely and wholly eject all of the gas in the cylinder therefrom, a novel construction being provided for this purpose which at the extreme end of the compression stroke of the piston forces all of the gas within the cylinder out and leaves no space between the check valve which holds compressed gas against return to the cylinder and the piston so that a very high efficiency is attained.

For an understanding of the invention whereby these results as well as many others not at this time particularly stated are attained, reference may be had to the following description taken in connection with the accompanying drawings in which:

Fig. 1 is a partial side elevation and vertical section of the compressor made in accordance with my invention.

Fig. 2 is an enlarged fragmentary vertical section through the upper end of the compressor cylinder, the piston being at the extreme of its compression stroke.

Fig. 3 is an under plan view of the housing head over the check valve plate located at the upper end of the compressor cylinder.

Fig. 4 is a plan view of one of the elements of the valve means used at the upper end of the compressor piston.

Fig. 5 is a plan of the check valve plate at the upper end of the compressor cylinder.

Fig. 6 is a plan view of a washer associated with the member shown in Fig. 4, and

Fig. 7 is a side elevation of one of the spiral band springs used to normally hold the check valve shown in Fig. 5 in lower position.

Like reference characters refer to like parts in the different figures of the drawings.

In the construction of the compressor, a crank case 1 is provided having a closed end, the opposite end of which is also closed by a casting 2. The shaft 3 of the compressor, which is driven from any suitable source of power, is connected to or formed with the usual crank indicated in dotted lines in Fig. 1 to which the connecting rod 4 is secured in the usual manner, the same extending upwardly into the lower end of a cylinder 5 located over the crank case 1.

The upper end of the cylinder 5 carries a head plate 6 having a central opening 7 therein, this opening being of frusto-conical shape as shown. Over the plate 6, a head 8 is positioned and both the head 8 and the plate 6 are secured to the cylinder 5 by means of the usual cap screws shown in Figs. 1 and 2. The head 8 is formed at its middle portion with a raised section 8* under which is a chamber 9 made between the head 8 and the plate 6 over the opening 7 described, and an outlet pipe 10 threads into the upper end of the raised section 8* of the head 8.

The piston 11 is located within the cylinder 5 and is adapted to be reciprocated in the cylinder, having the usual wrist pin connection 12 passing through the upper end of the connecting rod 4. In the head 13 of the piston a number of vertical openings 14 are made around the central vertical axis of said head and through the center of the head 13 an opening is made for the passage of a threaded stem 15 which receives a nut 16 at its lower end and is equipped with a frusto-conical head 17 at its upper end above the head 13 of the piston 11.

A washer 18 of thin metal is located around the stem 15 and lies over the upper ends of the openings 14 made through the piston head 13. It is located under the head 17 and between it and the under side of said head 17 a member 19 of flat metal is located having a

central opening for the passage of the stem 15, and, at spaced apart points in its circumference, having spring fingers 20 partially cut therefrom and bent downwardly so as to lie in a plane below the plane of the body of part 19. These fingers rest on the upper side of the washer 18 and normally hold the washer in lower position where it will close the upper ends of the vertical passages 14.

10 A flat valve plate 21, circular in form, is located over the upper end of opening 7 through the head plate 6, previously described. A housing member 22 for the valve plate lies within the chamber 9 and is permanently secured to the plate 6 at its upper side by means of screws as shown in Fig. 2. In the under side of the housing member 22 a shallow circular recess 23 is made and a plurality of openings 24 are bored upwardly from the recess into the member 22 in which spiral band springs 24 are inserted the same bearing at their lower ends with pressure against the plate 21 so as to force the same in a downward direction. In the flange surrounding the recess 23 in the lower side of the housing member 22 a number of radial shallow and wide outlet slots 25 are cut the purpose of which will later appear.

15 The gas which is to be compressed is received within the crank case 1 the details of construction by which it is carried into said crank case not being shown. It is evident that upon the down stroke of piston 11 valve plate 21 will close the upper end of the opening 7 through the pressure of the springs 24, in addition to which there is the pressure of the compressed gas whatever it may be above such plate. As the piston moves downwardly the washer 18 will be elevated against the force of the spring fingers 20 so that the gas below the piston can move upwardly through the opening 14 and into the cylinder 5 above the piston. On the reverse stroke of the piston the washer or ring 18 will drop to the closing position for the passages 14, being normally forced thereto by spring fingers 20 and aided by the higher pressure of the gas above the piston so that for the gas above the piston to escape it must pass through the opening 7, elevating the plate 21 against the force of springs 24, and passing into the chamber 9 through the slots 25 and thence outwardly through the pipe 10 to any suitable container, reservoir or in refrigerating apparatus to the coil or other apparatus where it is permitted to expand and thus withdraw heat from the surrounding space and perform its refrigerating functions. It will be noted that at the completion of the up stroke of 20 the piston the head 17 completely fills the opening 7 and its upper end bears against the lower side of the plate 21. All of the gas within the cylinder above the piston 11 is forced beyond and past the plate 21. There 25 is no loss of efficiency or capacity due to

spaces between the piston and the check valve plate wherein gas can be raised to a high pressure and then on the return stroke of the piston allowed to expand and thus reduce the efficiency of the apparatus. In addition the valve mechanisms used are particularly simple and effective and from their construction are durable and are not liable to get out of order. The invention is defined in the appended claims and is to be considered as comprehensive on all forms of structure coming within their scope.

70 I claim:

75 A compressor comprising, a cylinder having an open end, a piston reciprocable in said cylinder, a plate covering the open end of said cylinder and having a passage therethru, a disk located over said passage on the outer side of said plate, a housing member having a recess in its under side and outlet openings therefrom, said member being detachably fastened against the outer surface of said plate over said disk, a cylinder head located over said plate and having a chamber enclosing said housing and also having a passage 80 communicating with said chamber, and means for fastening both said cylinder head and said plate to the cylinder.

85 In testimony whereof I affix my signature.
